UNITED STATES PATENT OFFICE

2,556,633

LOOSE-SHEET HOLDER

Richard Fitz Power, Hampstead, London, and
Harold Arthur Cherry, Harborne, Birmingham,
England, assignors to Kalamazoo Limited,
Birmingham, England

Application October 8, 1948, Serial No. 53,526
In Great Britain October 31, 1947

2 Claims. (Cl. 129—16)

1

This invention has for its object to provide an improved loose sheet holder of the kind commonly termed a posting tray, such trays being used in offices for temporarily holding an assembly of leaves taken from a loose-leaf ledger or the like while entries are being made thereon.

In the accompanying drawings,

Figure 1 is a plan view of a loose sheet holder constructed in accordance with the invention;

Figure 2 is a cross section of the holder taken on the line A—A of Figure 1;

Figure 3 is a longitudinal section of the holder taken on the line B—B of Figure 1;

Figure 4 is an end elevation of the holder;

Figure 5 is a section taken on the line C—C of Figure 3;

Figure 6 is a section taken on the line D—D of Figure 5.

In one convenient manner of carrying the invention into effect, there is provided a sheet metal base 1 of rectangular form having side and end flanges 2 and 3. At or near one end of the base there is secured a sheet metal support 4 for the pile of paper sheets to be carried on the base, this support being inclined rearwardly at a convenient angle to the vertical as shown in Figure 3. In the base there are arranged a pair of racks 5 each having a corrugated upper surface. These racks are disposed at a convenient distance apart and parallel with the longitudinal side edges of the base 1. Also the racks are sunk beneath the upper surface 6 of the base by being accommodated in channels 7 formed therein. Usually the pile of paper sheets to be supported edgewise on the base and with its rear face in contact with the support 4, is divided into sections by index sheets made from stiff cardboard or other suitable material. One of such index sheets is shown at 8 and each index sheet is formed at its lower edge with a pair of tongue pieces 9 which engage the racks 5 and serve as fulcra on which the said index sheets can pivot.

Along the centre of the base 1 is formed a gap or channel constituted by downwardly turned portions 10 which are adapted to receive parallel channel members 11. These channel members form guides for a slide consisting of a plate 12 having downwardly extending side and end flanges. Rollers 13 mounted on the side flanges of the slide are adapted to run in the guide channel members 11. To the slide is pivotally connected by means of a pin 14 another sheet metal support 15 which is complementary to the fixed support 4. This second support can be rocked about the pin 14 either into contact with the ad-

2

jacent face of the pile of paper sheets, this position being indicated by broken lines in Figure 3, or to an oppositely inclined position (shown in full lines) where it allows the pile of paper sheets to be divided into two groups in V-relation, the one group being supported by the fixed support 4 and the other by the movable support 15.

For actuating the slide 12 and the movable support 15, there is pivoted at 16 on the slide the lower end of a handle 17, and the upper end of the handle is arranged in slidable connection with the support 15, this latter connection being conveniently effected by the provision on the upper end of the handle 17 of a crosspiece 18 whose ends engage a pair of parallel guides 19 on the support. For securing the slide 12 in any desired position there is provided a frictional locking device under the control of a trigger or grip 20 on the handle. The trigger or grip is pivoted to the handle at 21 and is loaded by a spring pressed plunger 22. The said locking device comprises a pair of crossed levers 23 each of bell crank form and loaded by springs 24 and carried on a common pivot 25 and having their outer ends adapted to exert a wedging action on the sides of the guides 11 in the base. The other ends 26 of the levers lie adjacent to one end 27 of the trigger 20. The arrangement is such that when the trigger is actuated by the user its lower end 27 presses on the locking levers 23 and causes them to release the slide. On release of the trigger the springs 24 move the levers into their operative position. A pin 28 secured to the handle engages holes in the sides of the trigger to limit its movement under the action of the plunger 22.

When a pile of paper sheets and the associated index sheets are placed on the portion of the base between the supports 4 and 15, the handle 17 and trigger 20 are gripped by the user for the release of the slide and are then pushed forward, causing the movable support 15 to be pressed into contact with one side of the pile and also causing the pile to be pressed into contact with the fixed support 4. On releasing the handle the slide is automatically locked by the action of the springs 24 on the locking levers 23. To enable the paper sheets in the pile to be manipulated, the movable support 15 is rocked to its other position as shown in full lines in Figure 3, allowing the pile to be divided at any part into two parts which are then respectively supported in V-relation by the two supports.

To prevent lateral displacement of the pile of paper sheets, a pair of guards are provided 55 along the longitudinal sides of the base. Each

such guard consists of a bar 29 having its ends 30 bent downwardly at right angles. To enable paper and index sheets of different widths to be accommodated, the ends of the guards are attached to the base by connecting pieces 31 having a slidable connection 32 with the base. Further, to enable some sheets to be off-set relatively to others, the guards are preferably hinged at 33 to the base or to the said connecting pieces 31, so that either guard can be swung outwardly to a position in which its straight part can serve as a stop for the off-set sheets. The guards are retained in either position by providing a pin 34 on the guard which co-operates with a spring loaded plunger 35 as shown in Figure 4.

By this invention there is provided in a very satisfactory manner a holder which is adjustable to paper piles of different thicknesses, is easily portable and is generally well adapted to office requirements.

Having thus described our invention what we claim as new and desire to secure by Letters Patent is:

1. A loose sheet holder comprising in combination a base, a fixed sheet support arranged at an inclination to the vertical adjacent to one end of the base, a slide on the base, a movable sheet support pivotally attached to the slide, an actuating handle pivotally attached at one end to the slide and having at the other end a slidable connection with the movable sheet support, means for releasably securing the slide to the

base, and a trigger for releasing the slide-securing means, the trigger being pivotally attached to the handle and arranged with one end adjacent to the slide-securing means so that the trigger can be actuated by a hand gripping the handle to cause the said end of the trigger to act on and release the slide-securing means.

5 2. A loose leaf holder as claimed in claim 1, in which the slide-securing means comprise in combination fixed parts at the sides of the base, and a pair of spring loaded levers carried by the slide and shaped at their outer ends to exert a wedging action on the said fixed parts, the levers being situated adjacent to and operable 10 15 by the trigger.

RICHARD FITZ POWER.
HAROLD ARTHUR CHERRY.
